(57) **CLAIM**

I claim the ornamental design for a folding knife, as shown and described.

DESCRIPTION

FIG. 1 is a front elevation view of a folding knife showing my new design;

FIG. 2 is a rear elevation view thereof;

FIG. 3 is a top plan view thereof;

FIG. 4 is a left side elevation view of FIG. 1; and,

FIG. 5 is a perspective view thereof.

1 Claim, 1 Drawing Sheet

FIG: 1

FIG: 2

FIG: 3
